DEVICE FOR PACKING BULK PRODUCTS

Wydmer G. Alcock, 2026 SE. Sherman, and Horace H. Christensen, 6704 NE. Emerson, both of Portland, Oreg.

Filed Sept. 30, 1957, Ser. No. 687,171

4 Claims. (Cl. 53—384)

This invention relates to a method of packing bulk products, particularly butter to be stored in cold storage rooms prior to packing the same for merchandising.

The primary object of the invention is to provide a method of filling transparent bags, as polyethylene bags, with butter or butter like materials for storing, handling and shipping.

In the carrying out of the above object, the bag is placed in a mold container after the container has been sprayed internally with an adhesive and disinfecting material, such as chlorinated water.

In order to get the bag evenly distributed within the walls of the mold container, the bag is first placed over a collapsible form which shapes the bag approximately to the same dimension as the inside of the mold container. This makes it easy to lower the bag into the container, after which the form is collapsed so that the form can be removed.

The spray that was previously sprayed on the inner wall of the mold container has an attraction for the polyethylene bag, drawing the bag tightly against the inner surface of the container. Butter then can be packed into the bag in the mold container, after which the top of the bag is folded over and sealed in the usual manner. The mold container is then delivered to a cold storage room where the soft material is hardened by refrigeration, after which the same can be removed from the mold container but will be protected and sealed within the bag for shipment or storage.

In the processing of the butter into packages thereafter, the folds of the bag can be pulled apart and pulled away from the sides of the block of butter without sticking to the same.

The old method of packing the butter for storage was to coat the inside of the container with a spray, line the same with individual pieces of parchment by hand. On the removing of this parchment from the block of refrigerated butter, it had a tendency to adhere thereto making the process very slow and expensive.

With the old method, moisture tended to escape from the stored butter through and around the parchment sheets, but with our method of using the polyethylene bag, the product can be stored indefinitely without any noticeable loss of moisture content.

Other objects and advantages will become apparent in the following specification when considered in the light of the attached drawings, in which:

Figure 1 is an inverted side elevation of the collapsible form having a polyethylene bag pulled down over same, the form being in an expanded position, parts broken away for convenience of illustration.

Figure 2 is a side elevation which illustrates the form inverted and inside the mold container with parts broken away and in section for convenience of illustration.

Figure 3 is a vertical sectional view taken on line 3—3 of Figure 4 looking in the direction of the arrows with broken lines illustrating the position of the form when

2

collapsed for removing the same from the bag and container.

Figure 4 is a plan view of the structure shown in Figure 2, broken lines illustrating the position of the form 5 when collapsed.

Figure 5 is an enlarged vertical sectional view taken on line 5—5 of Figure 3 looking in the direction of the arrows.

Figure 6 is a semi-diagrammatic view which illustrates 10 the first fold of the bag after being filled.

Figure 7 is a view similar to Figure 6 which illustrates the second fold.

Figure 8 is a view similar to Figure 6 which illustrates the third fold.

Figure 9 is a perspective which shows the final fold and sealing, the sealing iron being illustrated by broken lines.

Figure 10 is an enlarged fragmentary sectional view, taken on line 10—10 of Figure 3 looking in the direction 20 of the arrows.

Figure 11 is an enlarged fragmentary sectional view, taken on line 11—11 of Figure 3 looking in the direction of the arrows.

Referring now to the drawings in detail wherein like 25 reference numerals indicate like parts throughout the several figures, the reference character 10 indicates generally the apparatus used in performing the process of packing bulk products in accordance with the invention.

A collapsible form F is used to place a polyethylene 30 bag 15 into a mold container 16.

We will first describe the structure of the collapsible form F. This form includes a plurality of side walls 17. The side walls 17 are hinged together at their corners 18 and midway their width at 19 in a vertical direction 35 by hinges 20, referring particularly to Figure 11.

Referring to Figure 10, forming a part of the hinges 20 are inwardly extending ears 21. The ears 21 are pivotally connected to the hinge pin 22. Vertically disposed bars 23 are connected to the ears 21, referring particularly 40 to Figures 3 and 10.

A centrally located base plate 24 is disposed within the form F and has a pedestal 25 fixedly secured thereto extending vertically centrally of the form F. A sleeve 26 is fixedly mounted to the pedestal 25 and supports pivotally mounted bars 27 on ears 28 formed on the sleeve 26. Spaced from the sleeve 26 is a slidable sleeve 29, having integral outwardly extending ears 30 to support pivotally at 32 the bars 31. The outer ends 33 of the bars 27 are pivotally connected to the vertical bars 23 45 at 34. The slidable sleeve 29 is held in the position shown in Figure 3 by a locking device L.

The locking device L has a plunger 35 associated therewith having an opening 36 therein to embrace the pedestal 25. One side of the pedestal 25 has a notched groove 55 37 into which the inner edge 38 of the plunger 35 engages, referring particularly to Figure 5. A spring 39 holds the plunger 35 in the position shown engaging the inner edge 38 of the groove 37 of the pedestal 25, holding the sleeve 29 in a fixed position until the operator pushes against the end 40 of the plunger 35 thus overcoming the spring 39 and disengaging the edge 38 from the groove 37, permitting the sleeve 29 to be moved to an upper position, as illustrated by broken lines in Figure 3. When the sleeve 29 is moved upwardly the levers 27 and 31 and the vertical bars 23 are moved to the broken line position, pulling the side walls 17 to the broken line position as illustrated in Figures 3 and 4. This permits the removal of the collapsible form F from within the bag 15 after the bag 15 has been placed in the container 16.

70 A spring 41 engages between the sleeves 26 and 29 and tends to move the slidable sleeve 29 away from the

fixed sleeve 26, collapsing the form F. When it is desired to expand the form F in order to place the bag 15 over the same, the operator pushes down on the slideable sleeve 29 until the plunger 35 engages the groove 37 of the pedestal 25, which will hold the walls 17 of the form F in expanded position, as illustrated in Figures 3 and 4.

In the carrying out of our method of filling polyethylene bags, the first step is to form the bag 15 to be entered into the mold container 16, referring particularly to Figures 1, 2 and 4. The collapsible form F is inverted from the position shown in Figure 3 to that shown in Figure 1, the pedestal 25 passing down through an opening 42 in a supporting stand 43, bringing the top edges 44 of the side wall 17 of the form F down against the top 45 of the stand 43 for supporting the form F.

Next the bag 15 is placed over the form F and pulled down as illustrated, the surplus of the bag terminating in the folds 46. The next step is to spray the inner surface of the container 16 with a disinfectant having the characteristics of attracting the polyethylene bag towards the same when the bag 15 is placed in the container 16.

Figure 2 illustrates how the container 16 and form F, including the bag 15 are moved to a support 47 and the upper end 46 of the bag 15 folded down over the container 16. The next step is to release the locking device L, as above described, to permit the spring 41 to raise the movable sleeve 29 to the broken line position, including the bars 27, 31 and the side walls 17, referring particularly to Figures 3 and 4, permitting the removal of the form F from within the bag 15 within the container 16. When this is done the bag 15 and container 16 are filled with a product, such as butter delivered from the churn in plastic condition.

The next operation is to fold one side of the bag 15, referring to Figures 6, 7, 8 and 9. Figures 6, 7 and 8 are substantially diagrammatical drawings showing the folding of the bag 15. The first fold 48 is made as indicated. A second fold 49 is made. A third fold 50 follows, while the fourth fold brings the bag 15 to the position shown in Figure 9, all of the corners of the folds coming together at 51. At this time any suitable well known forked sealing iron 52, indicated by broken lines, is applied at this point, causing the polyethylene material to seal and lock all folds down together.

35
40
45

In Figure 9 we illustrate some of the structure of the container 16. One side of the container 16 is removable as indicated by the broken lines 53, so that when it is desired to remove the product and the bag 15 from the container 16 the removing of this one side facilitates the removal of the product.

Having thus described the preferred embodiment of the invention, it should be understood that numerous structural modifications and adaptations may be resorted to without departing from the scope of the appended claims.

What is claimed is:

1. A device for forming a bag to the walls of a mold comprising a plurality of vertical wall panels, means having vertically extending pivots hingedly securing the side edges of adjacent panels together, a horizontal base plate, a pedestal extending vertically from said base plate, and means extending radially outwardly from said pedestal connected to said panels for folding and unfolding said panels with respect to each other moving said panels radially with respect to said pedestal to form and support a bag.
2. A device as claimed in claim 1 wherein the means on said pedestal for moving said panels radially of said pedestal includes a stationary sleeve, a movable sleeve, and a plurality of links pivotally connected to said sleeves and to said panels.
3. A device as claimed in claim 2 wherein spring means are provided on said pedestal for normally biasing said movable sleeve away from said stationary sleeve.
4. A device as claimed in claim 3 wherein means are provided for locking said movable sleeve to said pedestal with said panels in expanded position.
